Patented Oct. 5, 1920.

UNITED STATES PATENT OFFICE.

BYRON E. PAGE AND CHARLEY C. HENDERSON, OF SPRING VALLEY, MINNESOTA.

DEVICE FOR TWISTING BAG-TIES.

1,354,836.

Specification of Letters Patent.

Patented Oct. 5, 1920.

Application filed December 30, 1919. Serial No. 348,305.

To all whom it may concern:

Be it known that we, BYRON E. PAGE and CHARLEY C. HENDERSON, citizens of the United States, residing at Spring Valley, in the county of Fillmore, State of Minnesota, have invented a new and useful Device for Twisting Bag-Ties, of which the following is a specification.

This invention relates to new and useful improvements in wire twisting devices, and it is the primary object of the invention to provide novel means for twisting wire ties employed for closing bags or the like.

A further object of the invention is to provide a device of this character having wire engaging fingers which will grasp the wire in a manner to eliminate any possibility of the wire becoming displaced or twisted from the device while the same is in operation.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:—

Figure 1 illustrates a perspective view of the device forming the subject matter of the invention, the same showing the application of the device in the twisting operation;

Fig. 2 illustrates a side elevational view of the device showing the operating handle in section;

Fig. 3 illustrates a fragmental view of the convoluted body associated with a wire tie; and

Fig. 4 illustrates a sectional view taken on line 4—4 of Fig. 2.

Fig. 5 illustrates a sectional view taken on line 5—5 of Fig. 4.

Referring to the drawing in detail, the reference character 5 designates the body portion of the device, the same being formed of any suitable material twisted to form a spiral or convoluted body.

One end of the body portion 5 is bifurcated to provide opposed gripping fingers 7, the bifurcated portion being bent inwardly to overlie a portion of the body portion 5, the fingers 6 thereof extending slightly outward, as indicated by Fig. 2 of the drawing,

so that the fingers may be readily inserted into the wire loops of the bag tie operated on.

The opposite extremity of the body portion 5 is provided with a reduced portion 8 to provide a bearing for the washer 9, which is secured thereto for restricting movement of the movable handle, with relation to the body portion 5.

Operating longitudinally of the body portion 5 is an operating handle 13, which is relatively long and shaped to be conveniently grasped by the operator, the forward portion of said handle being provided with cut out portions 14 disposed diametrically opposite each other, and in the extreme end thereof, which cut out portions provide bearings for the rollers 15 and 16.

These rollers 15 and 16 are supported in spaced relation with each other to engage opposite sides of the body portion 5, to cause the body portion 5 to revolve when the operating handle 13 is moved longitudinally thereof, there being a stop 17 provided in the outer or wire engaging end of the body portion 5, which stop engages the rollers 15 and 16 to restrict longitudinal movement of the handle 13 with relation to the body portion 5.

Supported on one end of the operating handle 13 is a securing collar 18, which collar is provided with an inwardly extending flange 19 adapted to overlie the ends of the spaced rollers 15 and 16 to hold the rollers in their proper operating positions within the cut out portions 14.

As shown, the operating handle 13 is provided with a central bore through which the body portion 5 operates, the bore being however provided with the metallic tubular member 19 which tubular member receives the wear caused by the operation of the body portion 5, through the handle, thus increasing the life of the handle.

In operation it is to be understood that the device forming the subject matter of the present invention is particularly adapted for use in twisting wire bag ties, the ends of which ties are provided with suitable loops, as indicated by Fig. 3 of the drawing, the loops being formed in the ties in the manufacture thereof, and which loops are of a size to be conveniently grasped by the fingers 7 which secure the wire to the twisting device.

The tie is now positioned over the mouth

of a bag, in a manner as indicated by Fig. 1 of the drawing, the operating handle being positioned adjacent the fingered end of the body portion. It will thus be seen that 5 when the operating handle is in this position, movement of the handle toward the rear end of the body, as accomplished by a pull on the operating handle, the body portion is caused to revolve to accomplish 10 the twisting of the tie to lock the mouth of the bag closed.

Having thus described the invention, what we claim as new is:—

1. In a wire twisting device, a spiral body 15 portion, wire twisting fingers provided on one end of the body portion, an operating handle adapted to move over the twisted body portion, said operating handle having recesses formed adjacent to one of the ends 20 thereof, a pair of spaced rollers having their ends disposed in the recesses, a securing collar positioned over one end of the operating handle, and said securing collar having an inwardly extending flange adapt- 25 ed to overlie the recesses to prevent displacement of the rollers, and means for restrict-

ing movement of the handle over the body portion.

2. In a wire twisting device, a spiral body portion, wire twisting fingers provided on 30 one end of the body portion, an operating handle adapted to move over the spiral body portion, said operating handle having a central bore, a metallic tubular member positioned in the bore and having cut out por- 35 tions formed adjacent to one end thereof, the cut out portions being disposed opposite each other, roller members positioned in the cut out portions and adapted to contact with the spiral body portion, and means 40 positioned over one end of the operating handle and adapted to overlie portions of the rollers to prevent displacement of the rollers.

In testimony that we claim the foregoing 45 as our own, we have hereto affixed our signatures in the presence of two witnesses.

BYRON E. PAGE.

CHARLEY C. HENDERSON.
